SUBSURFACE WELL BORE VALVE APPARATUS

Martin B. Conrad, Downey, Calif., assignor to Baker Oil Tools, Inc., Los Angeles, Calif., a corporation of California

Application January 30, 1956, Serial No. 562,235

18 Claims. (Cl. 251—149)

The present invention relates to valve apparatus, and more particularly to valve apparatus adapted to be disposed in well bores to control the flow of fluids therein.

Valve apparatus may be incorporated in a tubular string disposed in a well bore to control the flow of fluid in the tubular string. For many applications, it is desirable for the passage or bore through the valve apparatus to be of relatively large size and free from restrictions, to avoid the retarding of fluid flow through the apparatus when open, and to minimize erosive wear on its parts. In fact, it is preferred to have the passage through the valve apparatus at least as large in diameter as the bore through the tubular string extending to the top of the hole. Despite the presence of a large diameter passage through the valve apparatus, certain of its portions, such as a valve head movable into and out of engagement with a companion valve seat, may be subject to erosive wear by fluid passing thereby.

Difficulties are encountered in attempting to provide a full opening through a valve apparatus of the character described, and in protecting its valve head against erosive wear. Part of the difficulty involves the limited maximum outside diameter of the valve apparatus that can be used, in view of the restrictions presented by well holes of relatively small size, or of small diameter casing, or similar pipe, therein.

An object of the present invention is to provide a valve apparatus adapted to be incorporated in a tubular string disposed in a well bore and extending to the top of the latter, in which the valve apparatus can be placed selectively in an open or closed position, the passage through the apparatus being of large diameter as compared to its outside diameter, the valve head being substantially fully protected from the fluent material flowing through the passage when open. In a more limited sense, the open passage through the valve apparatus can be at least as large in diameter as the inside diameter of the tubular string, the passage being unrestricted throughout its length.

Another object of the invention is to provide a valve apparatus adapted to be incorporated in a tubular string to be located in a well bore, the valve apparatus embodying a valve head movable into and out of engagement with a companion seat, in which the valve head can be positively cammed to an open position in response to rotation of the tubular string, and held positively in such open position protected from the fluent material flowing through the open valve apparatus.

A further object of the invention is to provide a valve apparatus for incorporation in a tubular string to be disposed in a well bore, the valve apparatus being readily shifted between open and closed positions in response to longitudinal movement of the tubular string, and in which the valve apparatus can be positively shifted to an open position in response to rotation of the tubular string, in the event fluid pressure tends to maintain the valve apparatus in closed condition.

An additional object of the invention is to provide a

2

valve apparatus for incorporation in a tubular string to be disposed in a well bore, which has a full, unobstructed passage therethrough when in open position, to insure unimpeded flow of fluid through the passage, the valve apparatus parts being strong and sturdy, despite the fact that the passage diameter is comparatively large compared to the over-all diameter of the valve apparatus, and the space for locating certain valve parts in the valve apparatus is comparatively small.

10 This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

15 Referring to the drawings:

Figure 1 is a longitudinal section showing an embodiment of the invention with the valve in fully open position;

Fig. 2 is a view similar to Fig. 1 disclosing the valve 20 in closed position;

Fig. 3 is a view similar to Fig. 1 with the valve parts in an open position preparatory to being shifted to the position disclosed in Fig. 1;

Fig. 4 is a cross-section taken along the line 4—4 on 25 Fig. 3;

Fig. 5 is a cross-section taken along the line 5—5 in Fig. 3;

Fig. 6 is an enlarged cross-section taken along the line 30 6—6 on Fig. 2;

Fig. 7 is an enlarged cross-section taken along the line 35 7—7 on Fig. 1;

Fig. 8 is a fragmentary section taken generally along the line 8—8 on Fig. 2.

The apparatus A disclosed in the drawings is adapted 40 to be incorporated in a tubular string B, such as a string of drill pipe or tubing, extending to the top of the well bore. The apparatus may be attached to the lower end of such a tubular string, the lower portion of the apparatus, in turn, being adapted to be secured to a lower tool C, which may be a well-packer that is to be anchored in packed-off condition against a well casing (not shown).

The valve apparatus includes an upper tubular mandrel 10, movable longitudinally with a housing structure 11 surrounding it and extending below a lower valve seat 50 12 on the mandrel to a substantial extent. A lower tubular mandrel 13 is telescopically arranged within the housing 11, being movable relatively upward therewithin to a position in which its upper end 14 confronts and is adjacent the lower end 12 of the upper mandrel. When in this position, the two mandrels 10, 13 form, in effect, a continuous passage 15 therethrough that has a relatively large diameter. The diameter of the passage may be at least equal to the internal diameter of the tubular string B itself.

The upper mandrel 10 is attached to the housing 11 and can rotate with respect thereto to a limited extent. Thus, the mandrel 10 has an external flange 16 adapted to engage an inner flange 17 on an upper housing member 18, the upper end of the mandrel flange 16 being engageable with the lower end of a nut 19 threaded into the upper end of the upper housing member 18, the head 20 of the nut engaging the end of the latter. The lower end of the nut 19 and the inner flange 17 of the housing form an internal groove 21 rotatably receiving the mandrel flange 16. The mandrel 10 can be turned with respect to the housing 18 to a limited extent. Thus, the flange portion 16 is cut away or is provided with a recess 65 70

22 to receive a transverse pin 23 welded to the housing 18, the pin being engageable with the opposite ends 24, 25 of the recess, to locate the valve parts in particular positions, in the manner described hereinbelow.

The upper housing member 18 extends downwardly, its lower end being threadedly secured to a lower housing member 26 having an inwardly directed flange 27 slidably engaging the periphery of the lower mandrel 13 above a flange 28 on the latter. This flange 28 is movable relatively downward with the lower mandrel 13, such downward movement being limited by engagement with an inwardly directed flange 29 on the lower nut 30 threaded onto the lower end of the lower housing member 26. The housing 11 and lower mandrel 13 can move longitudinally with respect to each other, as limited by engagement of the mandrel flange 28 with the lower nut flange 29 and the inwardly directed flange 27 of the lower housing member. However, the parts are prevented from rotating with respect to each other, by virtue of a longitudinally extended key 31 welded, or otherwise suitably secured, to the inner wall of the lower housing member 26 and relatively slidable in a keyway 32 provided in the lower mandrel flange 28 (Fig. 5).

The inside diameter of the upper tubular member 18 between its upper inwardly directed flange 17 and the upper end of the lower housing member 26 is substantially greater than the external diameter of the upper and lower mandrels 10, 13, to provide an annular space 33 therebetween in which a valve head 34 can be confined. This valve head is of a flapper valve type and is adapted to move upwardly into engagement with the companion seat 12 provided by the lower end of the upper mandrel 10, in order to close the passage 15 through the upper mandrel. This valve head is also engageable with the upper end 14 of the lower mandrel 13, to close the passage through the latter member, all as described hereinbelow.

The valve head 34 is disposed in a pendant position within the annular space 33, when the valve is in fully open position, the upper end of the valve head having a transversely extending arm or pivot 35 received within the bore 36 provided in the lower projection 37 of a valve supporting ring 38 that bears against the inner flange 17 of the housing 11. The ring 38 is held in its upper position against the flange 17 by a relatively thin spacer sleeve 39 engaging the inner wall of the upper housing portion 18, the lower end of the sleeve bearing against the upper end of the lower housing member 26, and its upper end bearing against the ring 38. The ring, itself, is prevented from rotating by a pin 40 extending into the ring and the inner housing flange 17. A leaf-spring arm 41 is struck inwardly from the sleeve 39, and bears against the outer surface of the valve head 34, tending to shift it inwardly of the mandrels 10, 13.

Leakage of fluid between the exterior of the upper mandrel 10 and the upper housing member 18 is prevented by a suitable seal ring 42, such as a rubber or rubber-like O ring, disposed in an internal groove 43 in the housing flange 17 and bearing against the periphery of the upper mandrel 10. Similarly, leakage of fluid between the lower mandrel 13 and the lower housing member 26 is prevented by a suitable seal ring 44, such as a rubber or rubber-like O ring, disposed in an internal groove 45 in the housing flange 27 and slidably sealing against the periphery of the lower mandrel 13 above its flange 28. Leakage of fluid through the threaded connection between the housing members 18, 26 may be prevented by a suitable side seal ring 46 provided in a groove 47 in the lower housing member 26 and engaging the inner wall of the upper housing member 18.

It is to be noted that the valve seat 12 at the lower end of the upper mandrel 10 is inclined to the axis of the apparatus by a substantial extent. The valve head 34 may be retained completely within the annular spaces 33 between the mandrels 10, 13 and the housing 11, and

when permitted to do so it can be shifted upwardly into engagement with the inclined valve seat 12, being positively held thereagainst by the bearing of the companion inclined upper end 14 of the lower mandrel 13 against the back surface 48 of the valve head. As disclosed in Fig. 1, the upper mandrel 10 and housing 11 have been moved in a downward direction relative to the lower mandrel 13, in which position the lower mandrel 13 is disposed completely across the valve head 34 to confine it entirely within the annular housing space 33. When the valve parts are in the positions described, the inclined ends 12, 14 of the upper and lower mandrels 10, 13 are closely adjacent to one another, and fluids can then pass freely through the full opening 15 in the mandrels in both longitudinal directions.

When the valve apparatus is to be closed, it is only necessary to elevate the tubular string B, which will lift the upper mandrel 10 and housing 11 with respect to the lower mandrel 13, the housing being elevated to the extent determined by engagement of the lower nut flange 29 with the lower mandrel flange 28, such as disclosed in Fig. 3. When the parts are in this position, the upper end 14 of the lower mandrel is disposed below the depending valve head 34, allowing the leaf spring 41 to shift the valve head inwardly, in which it will be disposed in an inclined state across the upper end of the lower mandrel member 13. At this time the upper mandrel member 10 still occupies the rotational position with respect to the lower member 13 disclosed in Fig. 1. With the valve head 34 extending in an inclined position partly across the upper end 14 of the lower mandrel, the tubular B string, upper mandrel 10, and housing 11 need merely be lowered once again with respect to the lower mandrel 13, such lowering movement carrying the valve head 34 downwardly into engagement with the upper end 14 of the lower mandrel, causing the latter to swing the valve head upwardly about its pivot 35 into engagement with the valve seat 12 at the lower end of the upper mandrel 10. Downward movement of the upper mandrel 10 and housing 11 with respect to the lower housing 13 is limited by such engagement of the valve head 34 against the valve seat 12 and by the engagement of the back side 48 of the valve head against the upper end 14 of the lower mandrel 13. The parts then occupy the position disclosed in Fig. 2, in which the valve is in closed position, the valve head 34 being securely clamped between the upper and lower mandrels 10, 13. To prevent leakage of fluid between the valve seat 12 and the valve head 34, the latter may be provided with a marginal or circumferential groove 50 in its valve seating face 51, in which is positioned a seal ring 52, of rubber or rubber-like material, adapted to bear against the valve seat 12.

Assuming that the valve is to be reopened, it is merely necessary to elevate the tubular string B, which will carry the upper mandrel 10 and housing 11 upwardly with it relative to the lower mandrel 13, or again to the position disclosed in Fig. 3, the upper mandrel, however, still occupying the rotary position disclosed in Fig. 1. The valve head 34 may still be in sealing engagement with the valve seat 12. The tubular string B and upper mandrel 10 are then rotated in the proper direction to cause the lower portion 10a of the upper mandrel to engage the valve head 34 and cam it completely to one side and back into the annular space 33 within the housing member 11, the parts then occupying the positions disclosed in Fig. 3. At this time, the lower end of the depending valve head 34 is disposed above the upper end of the lower mandrel 13, whereupon the tubular string B, upper mandrel 10 and housing 11 can be lowered once again relative to the lower mandrel, the periphery of the lower mandrel 13 then sliding over the face 51 of the valve head and its end 14 engaging the end or valve seat 12 on the upper mandrel. Such engagement will cause the mandrels 10, 13 to rotate relative to each other, because of the inclination of the confronting ends 12, 14 of the upper

and lower mandrel, or, if desired, the upper mandrel 10 can be rotated with respect to the housing 11 back to the position shown in Fig. 1, which will then allow the mandrel 10 and housing 11 to be lowered to the fullest extent determined by engagement of the lower mandrel flange 28 with the lower housing flange 27, in which the lower mandrel 13 completely covers the valve head 34, and the confronting inclined edges 12, 14 of the mandrel are closely adjacent one another, all as disclosed in Fig. 1.

The lower mandrel 13 cannot shift rotationally with respect to the housing 11 and the valve head 34. However, the upper mandrel 10 can turn to a limited extent with respect to the housing 11 to secure the camming action of the valve head 34 back completely into the annular space 33 in the housing. The extent of rotation of the upper mandrel 10 with respect to the housing 11 is determined by engagement of the transverse housing pin 23 with the ends 24, 25 of the recess 22 in the mandrel flange 16. In the specific design disclosed in the drawings, rotation of the upper mandrel 10 to the right will place it in the position shown in Figs. 3 and 4, in which the valve head 34 is cammed completely out of the path of travel of the lower mandrel 13, and is confined within the annular space 33. Such position of the upper mandrel 10 is definitely determined by engagement of the end 24 of the flange recess with the transverse pin 23. On the other hand, rotation of the upper mandrel 10 to the left is limited by engagement of the other end 25 of the recess with the transverse pin 23, which will insure the location of the upper mandrel 10 with respect to the housing 11 in the position shown in Fig. 1, in which the upper and lower mandrels 10, 13 are closely adjacent one another, or in which position the valve head 34 can move upwardly into engagement with the valve seat 12 to close the passage 15 through the mandrels (Fig. 2).

In order to secure a large diameter passage 15 through the mandrels 10, 13, as compared to the outside diameter of the housing 11, the valve head 34 is curved to fit closely around the peripheral portions of the mandrels 10, 13 when disposed in a pendant position within the annular housing space 33, as shown most clearly in Fig. 7. In view of this curved form of the valve head 34, the valve seat 12 at the lower end of the upper mandrel 10, and the upper end 14 of the lower mandrel 13, must be curved to conform therewith, rather than such ends lying in straight diagonal planes. The seal ring 52 and its groove 50, of course, will also conform in curvature to the marginal portion of the valve seat engaging face 51 of the valve head.

If the valve head 34 were formed as a flat disk, it is evident that it could only be disposed completely to one side of the mandrels 10, 13, when the valve is in a completely open position, if the housing 11 were made substantially greater in diameter than indicated on the drawings, to provide a sufficient chordal space across the annular space 33 in the housing. In the present instance, the curving of the valve head 34 allows a smaller radial width of annular space 33 to be used, which can be provided by a much smaller diameter housing 11 than would be required by the use of a flat valve head.

In addition to enabling the passage diameter through the apparatus to be made relatively great in proportion to the outside diameter of the housing, the curving of the valve head 34 (so that it in effect constitutes a portion of a cylinder) greatly increases the strength of the valve head 34 and permits it to resist much greater pressures when in its closed position clamped between the valve seat 12 and the upper end 14 of the lower mandrel 13. As a result, it is even possible to make the valve head somewhat thinner than would be required if it were a flat disk, which contributes to the production of a valve apparatus with a much larger diameter through the mandrel passage 15 as compared to the over-all diameter of

the equipment, than could be provided in the event a flat disk were used.

- In the use of the apparatus A, it is secured to the lower end of the tubular string B, with its lower end attached 5 to the lower tool C, such as a well packer, and is run in the well bore with the parts all in the relative positions shown in Fig. 1. The valve head 34 is fully protected from the action of fluent materials passing through the mandrel passage 15, which is in a fully open condition. 10 At any time that it is desirous to close the valve, it is merely necessary to elevate the tubular string B, which will raise the upper mandrel 10 and housing 11, the lower mandrel 13 being prevented from moving upwardly by the lower tool C. Upward movement of the 15 upper mandrel 10 and housing 11 will occur until the valve head 34 is disposed above the upper end 14 of the lower mandrel 13, the spring arm 41 then projecting the valve head 34 inwardly until it extends partly across the lower mandrel 13. The apparatus is then lowered, the lower mandrel 13 swinging the head 34 upwardly until it engages the valve seat 12 and is backed up fully by the lower mandrel 13 itself (Fig. 2). Fluid is now prevented from passing in both longitudinal directions 20 through the upper and the lower mandrels 10, 13. 25 When it is desired to reopen the valve, it is merely necessary to elevate the tubular string B, to raise the upper mandrel 10 and housing 11 with respect to the lower mandrel 13, the lower mandrel then being disposed at a substantial distance below the valve head 34. 30 The valve head may drop away from the valve seat 12, or it may be held thereagainst by pressure below the apparatus. In any event, when the housing 11 has been shifted upwardly to its fullest extent with respect to the lower mandrel 13, the upper mandrel 10 need merely be rotated to the right and to the extent determined by engagement of the end 24 of the recess 22 with the limit pin 23. During such turning action, the lower portion 10a of the mandrel will engage the face 51 of the valve head and cam it in a lateral outward direction, swinging 35 it downwardly and outwardly about its pivot 35 until the valve head 34 again occupies a position completely within the annular space 33. 40 The tubular string B, upper mandrel 10 and housing 11 may again be relowered, the valve head 34 merely sliding over the periphery of the lower mandrel 13, which then holds it in its outward position. The tubular string B and upper mandrel 10 are then turned to the left, to the extent limited by engagement of the other end 25 of the recess 22 with the limit pin 23, which will 45 rotate the upper mandrel 10 out of the engagement with the valve head 34, and then permit the upper mandrel 10 and the housing 11 to be lowered to the fullest extent, determined by engagement of the lower housing flange 27 with the lower mandrel flange 28, in which the tapered curved ends 12, 14 of the upper and lower mandrels will 50 be closely adjacent one another. 55 When it is desired to pump fluent materials through the apparatus the valve parts are placed in the position shown in Fig. 1, in which the valve head 34 is fully protected. Such fluent materials, which may include sand or other abrasive particles used in performing a hydraulic fracturing operation in a well bore, may be pumped through the tubular string B and through the 60 valve apparatus A, continuing on down to the lower tool C for passage into the formation surrounding the well bore. The fluent materials cannot harm the valve head 34, since it is fully protected by the lower mandrel 13. If at any time it is desired to close the valve, the 65 parts need merely be manipulated in the manner described above, and then placed in the relative positions shown in Fig. 2. 70

Assuming that the apparatus is to be withdrawn from the well bore, elevation of the tubular string B will 75 elevate the upper mandrel 10 and housing 11 with re-

spect to the lower mandrel 13. When this occurs the spring arm 41 can project the valve head 34 in an inward direction. The valve head 34 may remain in open position or it may be caused by fluid pressure from below to swing upwardly into sealing engagement against the upper mandrel valve seat 12. The valve apparatus may be raised in the well bore with the parts in this closed position, which may be desirable, inasmuch as fluid, such as high pressure gases and the like, would then be prevented from flowing up through the tubular string B. If for any reason it is desired to prevent the valve head 13 from engaging its seat during upward movement of the apparatus in the well bore, then the tubular string B and upper mandrel 10 need merely be rotated with respect to the housing 11, causing the lower portion 16a of the upper mandrel to cam the valve head 34 completely out of the way and hold it in the annular housing spaced 34. In this position, which is shown in Fig. 3, the apparatus can be elevated in the well bore.

It is, accordingly, evident that a subsurface well bore valve apparatus has been provided which enables a very large diameter and unobstructed passage to be provided, as compared to the over-all diameter of the apparatus. The valve head 34 may be positively cammed out of the way to an ineffective and protected position, whenever desired, by the upper mandrel 10 itself. The mere fact that the valve seat 12 is substantially inclined with respect to the axis of the apparatus causes the lower portion 16a of the upper mandrel to function as a cam actuator. The curved valve member 34 enables the over-all dimensions of the apparatus to be kept relatively small, while increasing the strength of the valve head and insuring against its failure upon being subjected to substantial pressure.

The inventor claims:

1. In valve apparatus to be incorporated in a tubular string to be disposed in a well bore: tubular means having a valve seat disposed in a position inclined to the axis of the tubular means, wherein the full width of one portion of said seat is axially spaced substantially from the full width of a diametrically opposite portion of said seat; a valve head movable laterally of the axis of said tubular means into and out of engagement with said seat; and means mounting said tubular means for rotation relative to said valve head, to cause said tubular means, when rotated, selectively to engage and shift said valve head from said seat or to permit said valve head to engage said seat.

2. In valve apparatus to be incorporated in a tubular string to be disposed in a well bore: an inner tubular member; an outer tubular member receiving said inner member and rotatable with respect thereto; one of said members having a valve seat disposed in a position inclined to the axis of said members, wherein the full width of one portion of said seat is axially spaced substantially from the full width of a diametrically opposite portion of said seat; a valve head on the other of said members movable laterally of the axis of said members into and out of engagement with said seat; relative rotation between said members causing the inclined portion of said one member at said seat to cam said valve head laterally out of engagement with said seat.

3. In valve apparatus to be incorporated in a tubular string to be disposed in a well bore: an inner tubular member; an outer tubular member receiving said inner member and rotatable with respect thereto; one of said members having a valve seat disposed in a position inclined to the axis of said members, wherein the full width of one portion of said seat is axially spaced substantially from the full width of a diametrically opposite portion of said seat; a valve head on the other of said members movable laterally of the axis of said members into and out of engagement with said seat; relative rotation between said members causing the inclined portion of said one member at said seat to cam said valve head laterally

5 out of engagement with said seat; said members being relatively rotatable to an extent at which the periphery of said one member engages and holds said head completely out of the path of fluid flow through said one member.

4. In valve apparatus to be incorporated in a tubular string to be disposed in a well bore: an inner tubular member; an outer tubular member receiving said inner member and rotatable with respect thereto; one of said members having a valve seat inclined to the axis of said members; a valve head pivotally mounted on the other of said members and swingable laterally into and out of engagement with said inclined seat; relative rotation between said members causing the inclined portion of said one member at said seat to cam said valve head out of engagement with said seat; said members being relatively rotatable to an extent at which the periphery of said one member engages and holds said head completely out of the path of fluid flow through said one member.

5. In valve apparatus to be incorporated in a tubular string to be disposed in a well bore: an outer tubular member; an inner tubular member rotatably mounted within said outer member and having a valve seat inclined to the axis of said members; a valve pivotally mounted on said outer member and swingable into and out of engagement with said seat; relative rotation between said members causing the inclined portion of said inner member at said seat to cam said valve head out of engagement with said seat; said members being relatively rotatable to the extent at which the periphery of said inner member engages and holds said head completely out of the path of fluid flow through said inner member.

6. In valve apparatus to be incorporated in a tubular string to be disposed in a well bore: tubular means having a valve seat disposed in a position inclined to the axis of the tubular means, wherein the full width of one portion of said seat is axially spaced substantially from the full width of a diametrically opposite portion of said seat; a valve head movable laterally of the axis of said tubular means into and out of engagement with said seat; means mounting said tubular means for rotation relative to said valve head, to cause said tubular means, when rotated, selectively to engage and shift said valve head from said seat or to permit said valve head to engage said seat; and means movable longitudinally with respect to said tubular means into and out of engagement with said head to hold said head against said seat.

7. In valve apparatus to be incorporated in a tubular string to be disposed in a well bore: tubular means having a valve seat disposed in a position inclined to the axis of the tubular means, wherein the full width of one portion of said seat is axially spaced substantially from the full width of a diametrically opposite portion of said seat; a valve head movable laterally of the axis of said tubular means into and out of engagement with said seat; means mounting said tubular means for rotation relative to said valve head to cause said tubular means, when rotated, selectively to engage and shift said valve head from said seat or to permit said valve head to engage said seat; and means movable longitudinally with respect to said tubular means to a position across said valve head to prevent said head from engaging said seat.

8. In valve apparatus to be incorporated in a tubular string to be disposed in a well bore: tubular means having a valve seat inclined to the axis of the tubular means; a valve head movable laterally into and out of engagement with said seat; means mounting said tubular means for rotation relative to said valve head to cause said tubular means, when rotated, selectively to engage and shift valve head from said seat or to permit said valve head to engage said seat; and holding means movable longitudinally in one direction with respect to said tubular means into engagement with said head to hold said head against said seat, said holding means being movable relatively in the opposite direction to allow said tubular means to shift

said head from said seat, said holding means then being movable relatively in said one longitudinal direction across said valve head to prevent said head from engaging said seat.

9. In valve apparatus to be incorporated in a tubular string to be disposed in a well bore: an outer tubular member; a first inner tubular member rotatably mounted in said outer member; said inner member having a valve seat inclined to the axis of said members; a valve head carried by said outer member and movable laterally into engagement with said seat; relative rotation between said members causing the inclined portion of said inner member at said seat to cam said valve head out of engagement with said seat; and a second inner tubular member telescopically disposed in said outer member and movable relatively toward and away from said first inner member to engage and hold said valve head against said seat or to permit said valve head to move away from said seat.

10. In valve apparatus to be incorporated in a tubular string to be disposed in a well bore: an outer tubular member; a first inner tubular member rotatably mounted in said outer member; said inner member having a valve seat inclined to the axis of said members; a valve head carried by said outer member and movable laterally into engagement with said seat; relative rotation between said members causing the inclined portions of said inner member at said seat to cam said valve head out of engagement with said seat; a second inner member adapted to engage and hold said valve head against said seat; said second member being relatively movable away from said first member to permit said valve head to move away from said seat, whereupon said second member is relatively movable toward said first member and across said seat to hold said head out of engagement with said seat.

11. In valve apparatus to be incorporated in a tubular string to be disposed in a well bore: an outer tubular member; a first inner tubular member rotatably mounted in said outer member; said inner member having a valve seat inclined to the axis of said members; a valve head pivotally carried by said outer member and swingable into engagement with said seat; relative rotation between said members causing the inclined portion of said inner member at said seat to cam said valve head out of engagement with said seat; a second inner tubular member telescopically disposed in said outer member and movable relatively toward and away from said first inner member to engage and hold said valve head against said seat or to permit said valve head to move away from said seat; said first member and outer member being relatively rotatable to a position at which the periphery of said first inner member engages and holds said head completely out of the path of fluid flow through said first inner member.

12. In valve apparatus to be incorporated in a tubular string to be disposed in a well bore: an outer tubular member; a first inner tubular member rotatably mounted in said outer member; said inner member having a valve seat inclined to the axis of said members; a valve head pivotally carried by said outer member and swingable into engagement with said seat; relative rotation between said members causing the inclined portion of said inner member at said seat to cam said valve head out of engagement with said seat; a second inner tubular member telescopically disposed in said outer member and movable relatively toward and away from said first inner member to engage and hold said valve head against said seat or to permit said valve head to move away from said seat; said first member and outer member being relatively rotatable to a position at which the periphery of said first inner member engages and holds said head completely out of the path of fluid flow through said first inner member; said valve head being curved to conform generally to the periphery of said first inner member.

13. In valve apparatus to be incorporated in a tubular string to be disposed in a well bore: an outer tubular

member; an inner tubular member rotatably mounted within said outer member and having a valve seat inclined to the axis of said members; a valve pivotally mounted on said outer member and swingable into and out of engagement with said seat; relative rotation between said members causing the inclined portion of said inner member at said seat to cam said valve head out of engagement with said seat; said members being relatively rotatable to the extent at which the periphery of said inner member engages and holds said head completely out of the path of fluid flow through said inner member; said valve head being curved to conform to the periphery of said inner member.

14. In valve apparatus to be incorporated in a tubular string to be disposed in a well bore: an outer tubular member; a first inner tubular member rotatably mounted in said outer member; said inner member having a valve seat inclined to the axis of said members; a valve head pivotally carried by said outer member and swingable into engagement with said seat; relative rotation between said members causing the inclined portion of said inner member at said seat to cam said valve head out of engagement with said seat; a second inner tubular member telescopically disposed in said outer member and movable relatively toward said first inner member to engage and hold said valve head against said seat; said first member and outer member being relatively rotatable to a position at which the periphery of said first inner member engages and holds said head completely out of the path of fluid flow through said first inner member; said second member being relatively movable away from said first member to permit said valve head to be moved away from said seat by said first member, whereupon said second member is relatively movable toward said first member to dispose the periphery of said second member across said seat to hold said head out of engagement with said seat.

15. In valve apparatus to be incorporated in a tubular string to be disposed in a well bore: an outer tubular member; a first inner tubular member rotatably mounted in said outer member; said inner member having a valve seat inclined to the axis of said members; a valve head pivotally carried by said outer member and swingable into engagement with said seat; relative rotation between said members causing the inclined portion of said inner member at said seat to cam said valve head out of engagement with said seat; a second inner tubular member telescopically disposed in said outer member and movable relatively toward said first inner member to engage and hold said valve head against said seat; said first member and outer member being relatively rotatable to a position at which the periphery of said first inner member engages and holds said head completely out of the path of fluid flow through said first inner member; said second member being relatively movable away from said first member to permit said valve head to be moved away from said seat by said first member, whereupon said second member is movable relatively toward said first member to dispose the periphery of said second member across said seat to hold said head out of engagement with said seat.

16. In valve apparatus to be incorporated in a tubular string to be disposed in a well bore: an outer tubular member; a first inner tubular member rotatably mounted in said outer member; said inner member having a valve seat inclined to the axis of said members; a valve head pivotally carried by said outer member and swingable into engagement with said seat; relative rotation between said members causing the inclined portion of said inner member at said seat to cam said valve head out of engagement with said seat; a second inner tubular member telescopically disposed within and slidably splined to said outer member and movable relatively toward said first inner member to engage and hold said valve head

against said seat; said first member and outer member being relatively rotatable to a position at which the periphery of said first inner member engages and holds said head completely out of the path of fluid flow through said first inner member; said second member being relatively movable away from said first member to permit said valve head to be moved away from said seat by said first member, whereupon said second member is movable relatively toward said first member to dispose the periphery of said second member across said head to hold said head out of engagement with said seat; said valve head being curved to conform generally to the curvature of the peripheries of said first and second members; said second member having an inclined end conformable to and disposable adjacent the inclined seat on said first inner tubular member when said second member is disposed across said head.

17. In valve apparatus to be incorporated in a tubular string to be disposed in a well bore: an outer tubular member; a first inner tubular member rotatably mounted in said outer member; said inner member having a valve seat inclined to the axis of said members; a valve head pivotally carried by said outer member and swingable into engagement with said seat; relative rotation between said members causing the inclined portion of said inner member at said seat to cam said valve head out of engagement with said seat; a second inner tubular member telescopically disposed in said outer member and movable relatively toward and away from said first inner member to engage and hold said valve head against said seat or to permit said valve head to move away from said seat; said first member and outer member being relatively rotatable to a position at which the periphery of said first inner member engages and holds said head completely out of the path of fluid flow through said first inner member; and coengagable stop means on said first inner member and outer member for positively limiting relative rotation between said first member and outer member to a position at which said valve head can engage said seat or to a position at which the periphery of said first inner member engages said valve head to hold said valve head from said seat.

18. In valve apparatus to be incorporated in a tubular

string to be disposed in a well bore: an outer tubular member; a first inner tubular member rotatably mounted in said outer member; said inner member having a valve seat inclined to the axis of said members; a valve head pivotally carried by said outer member and swingable into engagement with said seat; relative rotation between said members causing the inclined portion of said inner member at said seat to cam said valve head out of engagement with said seat; a second inner tubular member telescopically disposed within and slidably splined to said outer member and movable relatively toward said first inner member to engage and hold said valve head against said seat; said first member and outer member being relatively rotatable to a position at which the periphery of said first inner member engages and holds said head completely out of the path of fluid flow through said first inner member; said second member being relatively movable away from said first member to permit said valve head to be moved away from said seat by said first member, whereupon said second member is movable relatively toward said first member to dispose the periphery of said second member across said head to hold said head out of engagement with said seat; said valve head being curved to conform generally to the curvature of the peripheries of said first and second members; said second member having an inclined end conformable to and disposable adjacent the inclined seat on said first inner tubular member when said second member is disposed across said head; and coengagable stop means on said first member and outer member for positively limiting relative rotation between said first member and outer member to a position in which said valve head can move into engagement with said seat or to a position at which the periphery of said first member holds said valve head completely out of the path of fluid flow through said inner members.
